US0D1075864S

(12) **United States Design Patent** (10) **Patent No.:** **US D1,075,864 S**
(45) **Date of Patent:** **** May 20, 2025**

(54) **CHARGING ROBOT**

(71) Applicant: **Zhejiang Anji Intelligent Electronics Holding Co., Ltd.**, Huzhou (CN)

(72) Inventors: **Jianpeng Li**, Huzhou (CN);
Zhenzhong Sun, Huzhou (CN)

(73) Assignee: **Zhejiang Anji Intelligent Electronics Holding Co., Ltd.**, Huzhou (CN)

(**) Term: **15 Years**

(21) Appl. No.: **29/873,112**

(22) Filed: **Mar. 24, 2023**

(30) **Foreign Application Priority Data**

Nov. 22, 2022 (CN) 202230780077.0

(51) **LOC (15) Cl.** **15-99**

(52) **U.S. Cl.**

USPC **D15/199**

(57) **CLAIM**

The ornamental design for a charging robot, as shown and described.

DESCRIPTION

FIG. 1 is a top perspective view of a charging robot, showing our new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the charging robot, which form no part of the claimed design.

1 Claim, 8 Drawing Sheets
